ABSTRACT

A composite lamp having relatively high efficacy and improved color richness and warmth. The lamp is comprised of a mercury or a metal halide lamp and a tungsten halogen lamp which are located in a common housing. The mercury or metal halide lamp is of relatively high efficacy and relatively high lumen output whereas the tungsten halogen lamp is of relatively lower efficacy and lower lumen output and is used primarily to improve the warmth and richness of the light output of the composite lamp. The tungsten halogen lamp is mounted directly beneath the mercury lamp and is physically much smaller so that only a minimal amount of the lumen output of the mercury lamp is obscured.

COMPOSITE LIGHT SOURCE

The present invention relates to a composite light source having an output of improved color richness and warmth and which appears to render objects illuminated with a sculptured or three dimensional quality.

Color richness is extremely important in many modern illumination applications such as in the illumination of goods or of an advertising display in a store. The warmth and richness of the light used may frequently determine the appeal which the goods on display will have to customers.

The richness and rendition of prior art light sources has not proven suitable for many applications. For instance it has been known in the prior art to utilize incandescent and fluorescent lamps in a common housing, but partly because of the light spread inherent in linear fluorescent sources the quality of the light emitted has not been satisfactory. Further, the light output of many widely used high efficacy high lumen output light sources such as mercury or metal halide lamps has proven to be too flat or cool for effective display illumination which requires warm light for effective viewing. On the other hand available light sources such as tungsten halogen sources which provide suitably warm and rich light from a color point of view are inherently low efficacy sources having a low lumen output per watt and are therefore too expensive for many commercial applications requiring extensive lighting.

It is thus an object of the present invention to provide a composite light source having a relatively high efficacy but also having improved color richness and warmth.

It is a further object of the invention to provide a composite light source including a supplementary lamp which will re-light instantaneously after power has been re-applied following a power failure.

As indicated above high efficacy lamps such as mercury or metal halide lamps provide a light which is too cool for many illumination applications whereas other lamps while providing light of suitable warmth are too low in efficacy to operate economically. According to the invention a light source having both high efficacy and suitable warmth is provided by utilizing a high lumen output mercury or metal halide lamp and a lower lumen output tungsten halogen lamp in a common housing. The source is of relatively high efficacy because most of the light output comes from the mercury or metal halide lamp but provides suitable warmth and color rendition because the light from the tungsten halogen lamp enriches the light emitted from the mercury lamp. The light emitted by the composite light source is of a very special quality and appears to give objects illuminated therewith a sculptured or three dimensional effect. The tungsten halogen lamp is mounted directly below the mercury lamp and is particularly well suited because its small size ensures that only a minimal amount of the light output of the mercury lamp is blocked. The lumen output of the tungsten halogen lamp is adjustable to control the degree of color richness of the composite source.

The invention will be better understood by referring to the accompanying drawings in which:

FIG. 1 is a sectional view of the improved light source of the invention.

FIG. 2 is a partly open perspective view of the light source.

The primary lamp 1 of the composite light source is of the high intensity discharge type and may be either a mercury or a metal halide type lamp. As discussed above it has been found that a mercury or metal halide lamp by itself does not provide suitable color richness for many commercial applications and therefore according to the invention the light emitted by lamp is supplemented by light emitted from lamp 2. Lamp 2 is a tungsten halogen lamp which is quite small in physical size, so that it obscures only a small portion of the light emitted from lamp 1.

According to the invention lamps 1 and 2 are both mounted in housing 5 with lamp 2 being disposed directly beneath lamp 1. Housing 5 may assume a variety of shapes and may for instance be square, round, circular, or rectangular, the circular embodiment shown in FIGS. 1 and 2 being illustrative only. Additionally, the fixture 5 may be mounted in a variety of ways as is known to those skilled in the art.

Member 3 is a reflector for the light emitted from lamp 1 and in the circular embodiment shown takes the form of a portion of a cone. Member 3 may for instance be made of metal and is polished on its inside surface to reflect the emitted light.

Support bar 6 runs across the center of the housing beneath lamp 1 and if desired may be a hollow tube along which electrical conductors to lamp 2 are run. It is not necessary for support bar 6 to extend all the way across the housing as shown. In the preferred embodiment lamp 2 is tubular in shape as shown and is mounted in reflector 9 which may be an elliptical, parabolic or spherical reflector. Reflector 9 with lamp 2 therein is mounted on support bar 6 via mounting means 8 which may be any conventional clamping means.

The electrical components associated with the lamps may be housed in the compartment formed between a wall of housing 5 and reflector 3. Capacitor 11 and ballast 12 necessary for the operation of mercury lamp 1 are shown strapped to the housing wall by straps 15 and 16. A voltage control device 13 such as a rheostat or a solid state voltage control device is shown mounted on reflector 3. This device is connected in the voltage supply circuit to tungsten halogen lamp 2 and control knob 14 is adjustable to supply a desired voltage to lamp 2. If it is desired to control the voltage to lamp 2 remotely then device 13 as well as the other electrical components may be located outside of and remotely from the housing 5. The connections between components 11, 12, and 13 and lamps 1 and 2 are conventional and have not been shown in the drawings.

The amount of color richness or warmth of the composite light source may be controlled by adjusting knob 14. Thus in different applications it may be desired to bring out different colors in varying amounts and this can be achieved by adjustment of the knob 14 which controls the lumen output of lamp 2. Thus the color rendition of the lamp may be modulated to suit a particular application.

60 The diffuser 7 may be metallic or plastic and to prevent light loss directly below tungsten halogen lamp 2 diffuser 7 has a central hole 10 therein.

Mercury lamp 1 has a lifetime of approximately 24,000 hours. The lifetime of the tungsten halogen lamp if it were run at rated voltage would be many times less than this. However a relatively small decrease in the operating voltage of this lamp results in a large increase in lifetime. It has been found that run-

ning a tungsten halogen lamp which is rated at 120 volts at between 95 to 100 volts increases the lamp's lifetime between 10 and 20 times. Thus by proper choice of operating voltage the lifetime of the tungsten halogen lamp may be made substantially equal to the life of the mercury lamp. Additionally, a characteristic of tungsten halogen lamps which results from the halogen cycle principle on which the lamps work is that they do not blacken and therefore maintain their initial light output throughout life. Since the lumen output of the mercury lamp decreases with age an additional function of voltage control device 13 is that it can be adjusted so that the relative light outputs of lamps 1 and 2 are maintained at a desired value as the lamps age.

Specific lamps are chosen according to the invention so that the lumen output of the higher efficacy mercury or metal halide lamp is substantially greater than the lumen output of the lower efficacy tungsten halogen lamp. While it will be apparent to those skilled in the art that many different specific lamp wattages and shapes may be used without departing from the scope of the invention in a preferred embodiment a 175 watt mercury lamp denoted as BT 28 having a mogul base was used. This lamp is eight and one-half inches long and three and one-half inches in diameter at its widest part. A tubular tungsten halogen lamp denoted as T4 was used and this lamp is three and one-half inches long and one-half inch in diameter. Hence it is seen that the dimensions of the tungsten halogen lamp are quite small compared to those of the mercury lamp. The 175 watt mercury lamp emits approximately 7,000 lumens of light while the 300 watt quartz halogen lamp which is inherently a lower efficacy lamp than the mercury lamp emits approximately 2,500 lumens when operated at between 95 and 100 volts.

The light resulting from the particular combination of lamps is observed to be of a special quality having improved color rendition and richness and giving illuminated objects a sculptured effect.

Further, the composite light source has the capability of being able to re-light instantaneously when power is re-applied after a power failure or when turned on at the beginning of the day. Thus while mercury lamp 1 will always take four or five minutes after power is applied for the arc to strike the tungsten halogen lamp

will light instantaneously and thus provide illumination sooner than if the mercury lamp were used by itself.

While I have disclosed and described the preferred embodiments of my invention, I wish it understood that I do not intend to be restricted solely thereto, but that I do intend to include all embodiments thereof which would be apparent to one skilled in the art and which come within the spirit and scope of my invention.

What is claimed is:

- 10 1. A color modulatable composite light source comprising a mercury lamp and an inherently lower efficacy tungsten halogen lamp having a rated voltage, a housing in which said lamps are enclosed and which includes at least a reflector for reflecting the light emitted by said lamps, said tungsten halogen lamp being mounted in said housing directly beneath said mercury lamp and being substantially smaller in physical size than said mercury lamp so that it obscures only a minimal amount of the lumen output of said mercury lamp, means for simultaneously supplying electrical energy to said lamps in respective amounts to cause said mercury lamp to have a substantially greater lumen output than said tungsten halogen lamp, and color modulator means comprising a manually operable means for varying the amount of electrical energy fed to said tungsten halogen lamp to vary the color output of the light source.
- 15 2. A color modulatable composite light source comprising a metal halide lamp and an inherently lower efficacy tungsten halogen lamp having a rated voltage, a housing in which said lamps are enclosed and which includes at least a reflector for reflecting the light emitted by said lamps, said tungsten halogen lamp being mounted in said housing directly beneath said metal halide lamp and being substantially smaller in physical size than said metal halide lamp so that it obscures only a minimal amount of the lumen output of said metal halide lamp, means for simultaneously supplying electrical energy to said lamps in respective amounts to cause said metal halide lamp to have a substantially greater lumen output than said tungsten halogen lamp, and color modulator means comprising a manually operable means for varying the amount of electrical energy fed to said tungsten halogen lamp to vary the color output of the light source.
